UNITED STATES PATENT OFFICE.

GUSTAVUS MILLHISER, OF RICHMOND, VIRGINIA, ASSIGNOR TO THE MILLHISER MANUFACTURING COMPANY, OF SAME PLACE.

DESIGN FOR A TOBACCO-PACKAGE.

SPECIFICATION forming part of Design No. 30,662, dated May 2, 1899.

Application filed March 11, 1899. Serial No. 708,765. Term of patent 14 years.

To all whom it may concern:

Be it known that I, GUSTAVUS MILLHISER, a citizen of the United States, residing at Richmond, in the county of Henrico and State of Virginia, have invented a certain new and useful Design for Tobacco-Packages, of which the following is a specification, reference being had therein to the accompanying drawings, in which—

10 Figures 1 and 2 are side elevations of opposite sides of the package, and Fig. 3 an edge elevation thereof.

The design consists of a substantially semi-circular cloth-covered package—that is to say, a package having a substantially straight upper or top edge 2 and a substantially semi-circular lower edge 3—the opposite faces of the package being substantially flat and par-

allel and the faces of the upper and lower edges being substantially straight or flat and lying at substantially right angles to the two side faces, a tapering flap 4 extending over the top edge 2 and down on one of the faces, and a string 5 extending vertically around the package.

25 I claim—

The design for a tobacco-package substantially as herein shown and described.

In testimony whereof I hereunto affix my signature, in the presence of two witnesses, 30 this 9th day of March, 1899.

GUSTAVUS MILLHISER.
